STONE DRESSER

Paul Weynand, San Antonio, Tex.

Application April 22, 1947, Serial No. 743,079

11 Claims. (Cl. 125—11)

1

This invention relates to improvements in stone dressers.

An important object of the invention is to eliminate the small, closely-spaced bearings of the stone dressers of the prior art, which wear out quickly, particularly when the machine rotates the stone at 10,000 R. P. M. or more. In the machine herein disclosed, the bearings are relatively large and well spaced apart and the assembly includes a long sleeve member, of substantial diameter.

Another important object is to provide a stone dresser wherein the pilot is centered upon the walls of an inverted conical recess in a tapered, spring-held seat, whereby the stone is retained in correct alignment so that the pilot will not become bent nor fit loosely within the bearings therefor and, in consequence will not wobble. This inverted conical recess permits the insertion of pilots of various sizes.

Still another important object is to eliminate the cylindrical dressing bars of the prior art.

A major object is to provide projections or lugs on the sleeve mentioned which fit into recesses or notches in the pilot, such as the notches in the tapered portion of the pilot disclosed in my United States Patent No. 2,387,787, dated October 30, 1945, and the notches in the tapered portion of the pilot disclosed in my application for United States patent, Serial No. 667,586, filed May 6, 1946, now Patent No. 2,443,489, dated June 15, 1948, for improvements in grinding tools. This arrangement prevents relative rotation of the pilot and seat.

Another major object is to provide spring means for the seat heretofore referred to, which means has a second function in connection with the lubrication of portions of the machine.

Other objects and advantages of the invention will be apparent during the course of the following detailed description of the invention, taken in connection with the accompanying drawings, forming a portion of this disclosure and in which drawings:

Fig. 1 is a front elevation of the novel stone dresser.

Fig. 2 is an end elevation thereof.

Fig. 3 is a rear elevation of the same.

Fig. 4 is a front elevation of a support forming part of the novel stone dresser.

Fig. 5 is a vertical section through a pilot-receiving and supporting means of the new dresser.

Fig. 6 is a top plan thereof.

Fig. 7 is a horizontal section thereof, taken upon the line 7—7 of Fig. 6.

2

Fig. 8 is a vertical section through a dressing bar receiving and positioning means of the new stone dresser.

Fig. 9 is a horizontal section thereof, upon substantially the line 9—9 of Fig. 8.

Fig. 10 is an elevation of a cover plate forming a part of the means shown in Figs. 8 and 9.

Fig. 11 is an elevation of a pressure plate forming a part of the means shown in Figs. 8 and 9.

10 Figs. 12, 13 and 14 are sectional views of the lower end of the dressing bar of Figs. 8 and 9 with a cutting device carried thereby.

Fig. 15 is a top plan of a calibrated member mounted upon the support of Figs. 1, 2 and 3.

15 Fig. 16 is a diagram of the electric wiring associated with the novel machine.

Fig. 17 is a view, partly in elevation and partly in vertical section of the pilot-receiving and supporting means of Fig. 5 but showing a pilot associated therewith and a fragment of one cutting device in a cutting position.

20 Fig. 18 is an elevation of the means of Figs. 5 and 17, showing a second cutting device in a cutting position.

25 Fig. 19 is a front elevation of the support of Fig. 4 but also including a guard wall portion with the latter swung to an open position.

Fig. 20 is a top plan of the same but the guard closed.

30 Figs. 21 and 22 are sections through the lower or free end of a dressing bar showing a modification of the carrying means for a cutting device, differing from the showing in Figs. 12, 13 and 14.

35 In the drawings, wherein for the purpose of illustration is shown a preferred embodiment of the invention, and a modification of one part of the invention, the letter A designates the novel stone dresser as a whole; B, a cutting device; C, one form of cutting device holding and locking 40 assembly; D, another form thereof; E, a pilot for association with the machine A; and F, an electric system for operation of the machine A.

The new stone dresser A includes a support 25, which may embody a bracket, shown merely in 45 Figs. 1 to 4 inclusive and Figs. 19 and 20 having a substantially vertically-disposed wall portion 26 and a rearwardly-extending, horizontally-disposed foot portion 27 with braces 28 extending from the wall portion 26 to the foot portion 27.

50 There may be provided also a forwardly extending, horizontally-disposed foot portion 29 extending from the bottom of the wall portion 26. If desired, there may be included a suitable movable guard wall portion 30 shown in Figs. 19 and 55 20, which, in the example shown, is outwardly

convex, is hingedly connected with the wall portion 26 at one end thereof, extends outward of that wall portion 26 and may be secured, by any approved latch means, to the opposite end of the wall portion 26. This wall portion 26 preferably supports all of the stone dresser mechanism, and it and the guard wall portion 30 partly encloses a substantial part of this mechanism.

This wall portion 26 may be provided with a plurality of openings as follows: A narrow vertically-extending groove 31, on substantially the vertical axis of the portion 26 and facing forwardly for receiving a lug for accurate positioning of the pilot-receiving and supporting means of the mechanism carried by the portion 26, a pivot means-accommodating perforation 32, a pivot means accommodating, narrow, horizontal slot 33, two major arcuate slots 34 and 35, one associated with the perforation 32 with its arc struck with the axis of the perforation 32 as center, and the other associated with the slot 33 having its arc struck with the center of the slot 33 as a center of the arc, and the arcuate portion of the slot 35 extending into a substantially horizontal slot portion, a plurality of screw-accommodating perforations 36 spaced from and disposed to either side of the groove 31, and a minor arcuate slot 37 associated with and paralleling the slot 34 and spaced between the slot 34 and its associated perforation 32. Preferably the upper edge of the wall portion 26 is curved, forming two arcuate faces 38 with their arcs struck with the axis of their nearest perforation 32 and slot 33 as centers. These faces 38 support strips or bands carrying calibrating indicia as will be subsequently explained and may have screw-threaded sockets extending inwardly therefrom for screw means to secure these strips or bands thereto. Arranged as they are, the two faces 38 join, forming a V-shaped recess 39.

Three portions of the mechanism are supported by the wall portion 26. First, there is the pilot-receiving and supporting means shown mainly in Fig. 5. Preferably, this means includes an outer, preferably cylindrical body portion 40, split longitudinally, so as to provide the slot 41, with a substantially smooth bore and cut away, at its outer face section opposite the face section containing the slot 41, so that a flat area 42 is provided, extending longitudinally of the body portion 40 from the center of which extends a lug 43 constructed and arranged to extend into the groove 31 in a snug fit therewith. Any approved means may be provided to cause the walls of the slot 41 to move toward each other and thus decrease the internal diameter of the body portion 40. In the example shown, there is provided a member 44 having a screw-threaded shank portion 45 and an exteriorly-carried handle portion 46 with the shank portion passing through suitable screw threaded perforation extending through the front wall section of the body portion 40 to either side of the slot 41 and opening into the slot 41. Moving the handle portion 46 in one direction causes the slot 41 to close somewhat (and thus reduces the interior diameter of the body portion 40), and moving the handle in the other direction permits the body portion 40 to spring into its former position so that this diameter is enlarged. It is preferred to close the slot by a resilient strip 47 as of rubber. In order to secure the body portion 40 to the wall portion 26, there may be provided spaced-apart screw-threaded sockets 48 in the body portion 40, extending from the flat area 42, to receive the shanks of screws 49 which also extend through

the perforations 36 in the wall portion 26. While these secure the portions 26 and 40 together, the contact of the lug 43 with the walls of the groove 31 and the contact of the flat area 42 with the face of the wall portion 40, contribute to retain the body portion against rocking or even against minor (but highly undesirable) vibrations.

Carried by the body portion 40 is an inner, preferably cylindrical body portion 50, somewhat longer than the former and, preferably, having a wall thinner than the wall of the portion 40. At adjacent its upper and lower ends, the portion 50 is interiorly screw-threaded, as at 51 and 52. Extending through the wall of the portion 50 are a suitable number of screw-threaded perforations, closed by screw-threaded closures 53. These perforations provide openings for the injection of suitable lubricating means, as oil, into the chamber defined, in part by the wall of the portion 50.

Supported by the portion 50 is a rotatable assembly 55 including a tubular portion 56, longer than the portion 50 and of an outer circumference less than the inner circumference of the portion 50 so that the former is spaced from the latter. At its lower end, the portion 56 is interiorly screw-threaded to receive a screw-threaded closure 57, including a lowermost, exteriorly-disposed head 58, having suitable means to facilitate turning, as the walls of wrench sockets 59, and an uppermost, exteriorly threaded, interiorly disposed shank 60. Extending downwardly from the upper face of the shank 60 is a sump 61 and from the base of the sump a small-diaetered vertical passageway 62 for drippings extends along the axial center of the closure 57 to the lower face of the head 58. Intermediate the length of the tubular portion 56 its outer face may be circumferentially grooved to receive a split ring 63 sprung into the groove but extending outwardly of the vertical plane of the outer peripheral surface of the portion 56, to limit upward movement of an abutment for an expansion coil spring to be subsequently described. Spaced above the groove last mentioned, the tubular portion 56 is provided with an outwardly extending, horizontal circumferential shoulder 64, for a purpose to be detailed. The upper end section of the portion 56 has a bevelled face 65 extending downwardly from its upper exterior edge to its inner face and constructed and arranged to receive, seated thereon, the tapered portion of the pilot disclosed in my United States Patent No. 2,387,787, dated October 30, 1945, and in my application Serial No. 667,586, filed May 6, 1946, referred to above. Extending radially from the upper end of the bevelled face 65 are small lugs 66, substantially 180° apart, to extend into the notches of the tapered portion disclosed in my United States patent and application for patent, referred to above. With these lugs 66 within the notches, the pilot will rotate with the rotatable assembly 55.

Spaced above the inner (or upper) end of the closure 57 is a seat 67 for the pilot shaft. This seat 67 is in the nature of a plunger slidable in the bore of the tubular portion 56, having an upper, bevelled face 68 adapted to receive the bevelled lower end of a pilot shaft and also functioning as a sump to receive grinding fluid drippings. From the axial center of the bevelled face 68 is a drippings passageway 69 opening into the lower face of the seat 67. Against this lower face bears the upper end of an expansion coil spring 70 with its lower end bearing against the upper face of the closure 57.

Extending about the periphery of the tubular portion 56 where the latter enters the lower end of the inner body portion 50, is a relatively thin sleeve 71 of suitable material to provide an oil seal, and having openings 73 to receive the lugs of a conventional wrench for the purpose of removing and placing the sleeve 71 when necessary. The sleeve preferably extends below the horizontal plane of the lower edge of the inner body portion 50 with the sockets mentioned being in this protruding section of the sleeve 71.

At the upper end section of the tubular portion 56 is a collar 72 which may have wrench lug-receiving openings substantially like the openings 73 and the collar has an outwardly-extending, horizontal flange portion 74 at its lower end, with the inner end section of the flange portion 74 resting upon the upper end of the shoulder 64. Externally of the collar 72 is a sleeve 75 of rubber or the like which functions in part as a closure for the lug-receiving openings 73.

The tubular portion 56 is preferably mounted for rotation by means of two ball bearing race assemblies 76 and 77, with parts of the casings thereof pressed on the portion 56 and extending to the interior face of the sleeve portion 50.

Outwardly of the assemblies 76 and 77 are suitable packing assemblies 78 and 79 and outwardly of the assemblies 78 and 79 are ring-shaped, split, closures 80 and 81. The closure 80 is exteriorly screw-threaded for cooperation with the screw threads 51 and the closure 81 has exterior screw threads for cooperation with the screw threads 52. Each closure 80 and 81 may be provided with wrench prong-receiving sockets in their outer faces.

Disposed upon the inner, movable portion of the casing of the ball bearing assembly 77 (that is, those parts of the casings pressed upon the tubular portion) is the lower end of an expansion coil spring 82 with its upper end bearing against a washer 83 and the latter, in turn, bearing against the protruding section of the split ring 63.

The second and third portions of the mechanism supported by the wall portion 26 are much alike and shown mainly in Figs. 8 to 11 inclusive. These second and third portions comprise the cutting devices supporting, adjusting and locking means, there being two of such means (a left-hand means and a right-hand means) differing only in the method by which they are movably supported by the support 25.

Each of the cutting device supporting, adjusting and locking means includes considerable of the structure shown in Figs. 8 and 9 particularly. Common structure includes a carrier and lever supporting member which may be an elongated bar 90, having a pivotal connection 91 at its upper end with a rod 92 slidably extending through the rear end of a sleeve 93, and rear end portion of which has a pivotal connection 94, spaced forwardly of the pivotal connection 91, with a depending dressing bar 95 which, as may be seen, particularly in Fig. 9, is polygonal in transverse section and not round. It has four major sides and four flattened corners and is slidably retained in a carrier 96. The carrier 96 is disposed intermediate the ends of the dressing bar 95 and the lower end of the dressing bar carries either the means B or C, to be subsequently described.

Referring again to the sleeve 93 which, with the rod 92 forms the lever, the free outer end of the former may carry a conventional two-button

electric switch later described and may house electric conductors of the electric system F.

Each carrier 96 includes a major body portion 97 which is preferably, a block of suitable metal, having a longitudinally-extending groove 98 in one face (the outer face) thereof, this groove being very slightly more than the greatest width of the dressing bar 95 for the greater part of its depth and walls of the groove 98 after being substantially parallel, converge forming substantially a right angle as may be seen in Fig. 9. The converging walls slidably receive two faces of the dressing bar. The other two faces of the latter are pressed by the converging faces of a longitudinal groove 99 in a pressure plate 100, shown in Figs. 9 and 11, having, in its face opposite the face from which extends the groove 99, a plurality of spring-receiving sockets 101.

A cover plate 102 covers the forward face of the major body portion 97 and covers the pressure plate 100. It is secured to the body portion 97 as by screws and a guide pin 103 may extend through it and into a socket in the pressure plate 100 to slidably retain the latter in position. The inner face of the cover plate is provided with a plurality of spaced-apart spring-receiving sockets 104 for expansion coil springs 105 which also extend into the aligning sockets 101 in the pressure plate, thus pressing the latter into good frictional contact with the dressing bar 95.

Two end plates 106 are provided (with suitable openings for the dressing bar 95) to close the ends of the carrier 96 and are secured thereto and may be secured to the cover plate 102 as by suitable screws. A packing sheet 107 may be disposed upon each of the inward faces of the end plates.

In order to limit movement of the dressing bar 95 in one direction, (downwardly) yet permit adjustments of such limit, an adjustable stop 108 may be provided, secured to one face of the dressing bar above the carrier 96. This stop 108 may be a slotted bar, adjustably secured to the dressing bar 95 by screws with their shanks passing through the slot and into screw-threaded sockets in the dressing bar, while their heads bear against the outer face of the slotted bar. It is obvious that downward movement of the dressing bar will be stopped by the lower end of the slotted bar abutting the upper end plate 106.

The left-hand cutting device supporting, adjusting and locking means includes one pivotal connection with the wall portion 26 of the support 25 and two slidable connections which also function to secure this means in adjusted positions with respect to the wall portion 26.

The pivotal connection is preferably a shank 110 having screw-threaded end portions 111 and 112 and a smooth intermediate portion 113. The screw-threaded end portion 111 extends into a screw-threaded opening in the elongated support bar 90, the smooth intermediate portion 113 is accommodated in the perforation 32 in the wall portion 26, and the screw-threaded end 112, protruding from the back of the wall portion 26, accommodates a nut 114 normally bearing against the rear face of the wall portion 26 and provided with suitable conventional wrench sockets.

One slidable connection is spaced from the pivotal connection mentioned and comprises a screw-threaded shank 115 with one end extending into a screw-threaded socket in the rear face of the carrier block or main body portion 97, its intermediate portion extending through a perforation in the elongated bar 90, then slidably

extending through the arcuate slot 37, and then into a screw-threaded opening through a nut 116, normally bearing against the rear face of the wall portion 26 and provided with wrench sockets.

The second slidable connection is spaced from the first slidable connection and with the latter between it and the pivotal connection last mentioned. Preferably it includes a shank 117, screw-threaded at its end portions 118 and 119 and with its intermediate smooth portion 120 encircled by a sleeve 121. The end portion 118 extends into a screw-threaded socket in the rear face of the carrier block or main body portion 97. The inner end of the sleeve may be outwardly flanged and extend into a circular groove in the face of the support bar 90 abutting the portion 97. Set screws 122 extend into the support bar 90 at opposite faces thereof and engage the sleeve 121, intermediate its ends. The sleeve extends, of course, into and through the arcuate slot 34 and its outer periphery, rearwardly of the wall 26 is screw-threaded to receive a nut 123. The screw-threaded end 119 of the shank 117 carries a handled nut 124 with a washer 125 interposed between the nuts 123 and 124. This provides for an exceptionally secure means to adjustably secure the carrier and the dressing bar in various positions with the shank 118 as a pivot. There are, as is now clear, three separate means to secure the carrier in a locked position so that it is not apt to become loosened, due to vibrations. By loosening the nuts 114, 116, 123 and 124, the carrier 96 and its dressing bar 95 together with the support bar 90 and the lever connections 91, 92 and 93, may be pivoted, as a whole, limited only by the lengths of the slots 34 and 37.

Now, referring to the connections of the right-hand cutting device supporting, adjusting and locking means, these connections differ from those of the left-hand means as may be seen, particularly in Fig. 3, only in the omission of the shank 115 and nut 116, but the smooth, intermediate portion 113 of the shank 110 extends through the slot 33 and not through a perforation and the sleeve 121 is adapted to extend through both the arcuate and straight portions of the slot 35. This permits both a pivotal movement of the right-hand cutting device supporting, adjusting and locking means, as well as a horizontal sliding of this particular means from left to right and vice versa.

In order to properly adjust the two cutting device supporting, adjusting and locking means, there is provided, for each edge 38 of the wall 26 a strip 130, as shown in Fig. 15 containing suitable indicia as the degree figures 131 and division marks 132. They may be secured to the edges 38 as by screws. An index in the form of an arm 133 may be secured to each support bar 90 and positioned to move over the strip 130 with which it is associated.

The cutting device B may be a diamond-pointed, screw-threaded shank 135 with a knurled head 136.

Referring to Figs. 12 to 14 inclusive, the preferred form of the cutting device holding and locking assembly C, is shown to include an interiorly screw-threaded, split sleeve 137 surrounding the intermediate portion of the shank 135 and extending into a suitable opening 138 in the dressing bar 95. This opening 138 preferably extends with its axis forming obtuse angles with the adjacent faces of the dressing bar, and its axis is inclined from the longitudinal axis of the

dressing bar, as shown in Fig. 12. Consequently the longitudinal axis of the shank 135 is also inclined with respect to the longitudinal axis of the dressing bar. A set screw 139 may be employed to assist in securing the split sleeve 137 in place and tends to compress it. Associated with the split sleeve 137 is a major locking device 140, comprising a shank 141, screw-threaded at one end and to which a knurled nut 142 is secured by means of the screw threads. The free end 143 of the shank 141 is enlarged over the intermediate portion of the shank with the enlarged end providing a cam surface at the junction of this end 143 and the intermediate portion of the shank. The shank 141 is constructed and arranged to be inserted into a suitable bore 144 in the dressing bar, spaced above the opening 138 and with its axis normal to the axis of the opening 138. This insertion may be made, since the nut 142 is removable. This nut bears against a block 145 which has a bore for the shank 141 and a substantially V-shaped slot in the face opposite its nut-contacting face, with the slot accommodating an edge portion of the dressing bar as may be seen in Fig. 14. As the shank 141 is drawn to the right in Fig. 14, upon tightening of the nut the cam surface bears against the sleeve 137, as is clear in Fig. 13, and causes tightening of the sleeve and prevents longitudinal movement thereof. Obviously rotation of the head 136 will feed the diamond point toward or away from the dressing bar 95.

Referring now to Figs. 21 and 22, wherein the modified form C of the cutting device holding and locking assembly D is shown, the same may be associated with the cutting device B and the dressing bar 95 described. A screw-threaded opening 150 extends through the dressing bar 95 adjacent its lower end, with the longitudinal axis thereof inclined with respect to the longitudinal axis of the dressing bar and forming obtuse angles with the adjacent faces of the dressing bar. Above this opening 150 is a second opening 151, normal thereto, and accommodating the enlarged free end 152 of a shank 153, with the intermediate portion of the latter reduced in circumference so that there is provided a recess 154 defined by the walls of the opening 151, intermediate portion of the shank 153 and inner end of the enlarged free end 152, in which recess is disposed an expansion coil spring 155 bearing at its inner end against the enlarged free end 152 and bearing at its outer end against a block 145' substantially similar to the block 145. The shank 153 extends through the block 145', is screw-threaded at its outer end, and accommodates a nut 156 which may bear against a washer 157 contacting the block 145'. Referring again to the enlarged free end 152 this is provided with a cam face constructed and arranged to engage the shank 135 of the abrasive device B and, when the nut 156 is tightened, hold the shank 135 against rotation.

The pilot E is shown in Figs. 17 and 18, merely by way of example and is described in detail in my United States Patent No. 2,387,787 referred to above. It includes a shank 160 which may be bevelled at its free end 161 and this end is adapted to seat upon the novel seat 68 of the stone dresser A. Notches described in my United States Patent No. 2,387,787 accommodate the lugs 69 and, above the notches, is the stone, such as the stone 163 to be worked. Above the stone 163 is shown a flexible coupling 164 having a recess to receive a suitable means, as the spindle or shaft 165 operatively connected with a suitable

source of power to rotate the spindle 165 and, consequently, the coupling 164, stone 163, shank 160 and the rotating portions of the novel stone dresser A.

The free end of each sleeve 93 may be provided with a conventional electric switch 170, with one pole connected, as shown in Fig. 16, with the power line conductor 171 and from the other connected with conductors 172 extending to one side of a suitable electric motor 173, there being a conductor 174 electrically connected with the other side of the motor and extending to the other power line conductor 175. The motor 173 is adapted to rotate the pilot, by means of the shaft 165.

It is now obvious that, by moving the handle 46 to cause the split cylindrical body portion 40 to expand circumferentially, the inner body portion 50 may be raised or lowered manually and the wall of body portion 40 again clamped thereabout. This provided vertical adjustment for the portion 50 with respect to the fixed body portion 40 and, of course, vertical adjustment of the portions carried by the portion 50. In Figs. 17 and 18 there are shown two vertical adjustments of the portion 50 with respect to the portion 40.

A very firm frictional engagement of the shank 160 with the seat 67 is provided, not only by the bevelled surface 68 of the latter, but the expansion coil spring 70 tends to force the seat 67 upwardly. This spring 70 also functions as an oil splasher for adjacent rotating portions of the machine, since oil may be introduced and drained through the openings closed by the screw-threaded closures 53.

In the event the left-hand cutting device supporting, adjusting and locking means is to be employed, the operator loosens the nuts 114, 116, 123 and 124 and this permits rotation of the means on the pivot 110. When the means has been swung to a proper position so that the stone 163 will not contact the diamond point when the former is placed in position for dressing, nuts 114 and 123 are thereupon tightened. By manipulation of the lever sleeve 93 (drawing down on the free end of the sleeve) the dressing bar will lower the cutting device B below a position to be taken by the stone. The pilot is next inserted as in Fig. 17. The handle 46 is next manipulated to permit the body portion 40 to expand circumferentially and the inner body portion 50 is lowered to a location where the stone is in position to be contacted by the diamond point. The portion 50 is now locked in position. Final adjustment of the dressing bar and adjustment of the cutting device B are next effected. The latter is now locked into position by the holding and locking means C or D, as the case may be, and the nuts 116 and 124 tightened. The shaft 165 is now operatively connected with the pilot E and the electric circuit to the motor 173 is closed by manipulation of the switch at the end of the lever sleeve 93. It is now clear that manual manipulation of this lever sleeve will cause proper contact of the diamond point with the stone.

In order to correct an error in the angle of the diamond-pointed shank of the cutting device, with respect to the stone's surface, the nut 116 is loosened and the set screws 122 manipulated to effect such correction, whereupon the nut 116 is again tightened.

Since the right-hand cutting device supporting, adjusting and locking means is employed, ma-

nipulation thereof is, in part, similar to that of the left-hand means, except that there is no intermediate nut and the entire means may be moved horizontally along the horizontal portion of the slot 35 and the horizontal slot 33 to cause the diamond point of this right-hand means to approach the stone along a horizontal line. Obviously, this right-hand means may take the vertical position shown or may take a position inclined from the vertical.

Various changes may be made to the forms of the invention herein shown and described without departing from the spirit of the invention or scope of the claims.

What is claimed is:

1. In a dresser for a stone mounted upon a pilot shaft, a support and pilot shaft-receiving-and-supporting means carried by the support and including an outer body portion having a longitudinal bore, an inner body portion, slidable longitudinally of said bore, means to retain said inner body portion in various selected positions longitudinally of said outer body portion, and a rotatable assembly, rotatably carried by said inner body portion, including a tubular portion having an open end, a pilot shaft-receiving seat within said tubular portion and slidable longitudinally of said tubular portion, and resilient means urging said seat toward said open end.
2. In a dresser for a stone mounted upon a pilot shaft, a support and pilot shaft-receiving-and-supporting means carried by the support and including an outer body portion having a longitudinal bore, an inner body portion, slidable longitudinally of said bore, means to retain said inner body portion in various selected positions longitudinally of said outer body portion, and a rotatable assembly, rotatably carried by said inner body portion, including a tubular portion having an open end and a closed end, a pilot shaft-receiving seat within said tubular portion spaced from both of said ends and slidable longitudinally of said tubular portion, and resilient means urging said seat toward said open end; said resilient means being disposed between said seat and said closed end.
3. In a dresser for a stone mounted upon a pilot shaft, a support and pilot shaft-receiving-and-supporting means carried by the support and including an outer body portion having a longitudinal bore, an inner body portion, slidable longitudinally of said bore, means to retain said inner body portion in various selected positions longitudinally of said outer body portion, and a rotatable assembly, rotatably carried by said inner body portion, including a tubular portion having an open end and a closed end, a pilot shaft-receiving seat within said tubular portion and slidable longitudinally of said tubular portion and having a beveled seating surface facing toward said open end and a lubricant receiving passageway extending from said surface to the surface of said seat facing said closed end, said last named surface, closed end and adjacent portions of said tubular portion defining a lubricant reservoir, said seat being slidable longitudinally of said tubular portion, and means to resiliently urge said seat toward said open end.

4. In a dresser for a stone mounted upon a pilot shaft, a support and pilot shaft-receiving-and-supporting means carried by the support and including an outer body portion having a longitudinal bore, an inner body portion, slidable longitudinally of said bore, means to retain said inner body portion in various selected positions lon-

11

itudinally of said outer body portion, and a rotatable assembly, rotatably carried by said inner body portion, including a tubular portion having an open end, spaced-apart friction-reducing means between said tubular portion and said inner body portion, including casings fixed to the outer periphery of said tubular portion, a spring abutment extending from the outer periphery of said tubular portion and spaced from one of said casings, an expansion coil spring bearing, at one end, against one of said casings and bearing, at its other end, against said abutment, a pilot shaft-receiving seat within said tubular portion and slidably longitudinally of said tubular portion, and resilient means urging said seat toward said open end.

5. In a dresser for a stone mounted upon a pilot shaft, a support and pilot shaft-receiving-and-supporting means carried by the support and including an outer body portion having a longitudinal bore, an inner body portion, slideable longitudinally of said bore, means to retain said inner body portion in various selected positions longitudinally of said outer body portion, and a rotatable assembly, rotatably carried by said inner body portion, including a tubular portion having an open end, spaced-apart friction reducing means between said tubular portion and said inner body portion, including innermost casings fixed to the outer periphery of said tubular portion and outermost casings fixed to the inner face of said inner body portion, said casings and the adjacent portions of said inner body portion and tubular portion providing an oil reservoir, a spring abutment extending from the outer periphery of said tubular portion and spaced from the innermost casing farthest from said open end, an expansion coil spring within said oil reservoir, bearing, at one end, against said last-named casing and bearing, at its other end, against said abutment, a pilot shaft-receiving seat within said tubular portion and slideable longitudinally of said tubular portion and resilient means urging said seat toward said open end.

6. In a dresser for a stone mounted upon a pilot shaft with the shaft having a recess at adjacent its juncture with the stone, said dresser including a support and pilot shaft-receiving-and-supporting means carried by the support and including an outer body portion having a longitudinal bore, an inner body portion, slideable longitudinally of said bore, means to retain said inner body portion in various selected positions longitudinally of said outer body portion, and a rotatable assembly, rotatably carried by said inner body portion, including a tubular portion having an open end provided with a lug constructed and arranged to extend into said recess, a pilot shaft-receiving seat within said tubular portion and slideable longitudinally of said tubular portion, and resilient means urging said seat toward said open end.

7. In a dresser for a stone mounted upon a pilot shaft, a support; pilot shaft-receiving-and-supporting means carried by said support, including a rotatable seat for said shaft; a dressing bar; a stone-dressing device carried thereby; and supporting, adjusting and locking means for said dressing bar, pivotally carried by said support to permit movement of said dressing bar so that the longitudinal axis of said dressing bar will intersect the axis of rotation of said seat, including an elongated bar pivoted to said support, a lever pivotally carried, at one end thereof, to one end of said bar, a pivotal connection between said

12

dressing bar and said lever, and a carrier supported by said elongated bar and provided with an opening slidably accommodating the intermediate portion of said dressing bar, said carrier having a spring-urged pressure plate bearing against said intermediate portion of said dressing bar.

8. In a dresser for a stone mounted upon a pilot shaft, a support; pilot shaft-receiving-and-supporting means carried by said support, including a rotatable seat for said shaft; a dressing bar, polygonal in transverse cross section; a stone-dressing device carried thereby; and supporting, adjusting and locking means for said dressing bar pivotally carried by said support to permit movement of said dressing bar so that the longitudinal axis of said dressing bar will intersect the axis of rotation of said seat, including an elongated bar pivoted to said support, a lever pivotally carried, at one end thereof, to one end of said bar, a pivotal connection between said dressing bar and said lever, and a carrier supported by said elongated bar and provided with an opening, of the same shape as the transverse cross sectional shape of said dressing bar, slidably accommodating the intermediate portion of said dressing bar, said carrier having a spring-urged pressure plate bearing against two adjacent faces of said intermediate portion of said dressing bar.

9. In a dresser for a stone mounted upon a pilot shaft, a support; pilot shaft-receiving-and-supporting means carried by said support, including a rotatable seat for said shaft; a dressing bar, polygonal in transverse cross section; a stone-dressing device carried thereby; and supporting, adjusting and locking means for said dressing bar, pivotally carried by said support to permit movement of said dressing bar so that the longitudinal axis of said dressing bar will intersect the axis of rotation of said seat, including an elongated bar pivoted to said support, a lever pivotally carried, at one end thereof, to one end of said bar, a pivotal connection between said dressing bar and said lever, and a carrier supported by said elongated bar and provided with an opening, of the same shape as the transverse cross sectional shape of said dressing bar, slidably accommodating the intermediate portion of said dressing bar, said carrier having a spring-urged pressure plate, provided with a substantially V-shaped recess, with the surfaces of said recess bearing against two adjacent faces of said intermediate portion of said dressing bar.

10. In a dresser for a stone mounted upon a pilot shaft, a support having an arcuate slot and a pivot-accommodating opening; pilot shaft-receiving-and-supporting means carried by said support, including a rotatable seat for said shaft; an elongated dressing bar; a stone-dressing device carried thereby; and supporting, adjusting and locking means for said dressing bar, pivotally carried by said support to permit movement of said dressing bar so that the longitudinal axis of said dressing bar will intersect the axis of rotation of said seat, including an elongated bar, a carrier mounted thereon with said dressing bar slidably longitudinally therethrough, a pivot extending through and outwardly of said pivot-accommodating opening, and secured at one end to said carrier and provided with screw threads at its other end, a nut upon said other end and normally bearing against said support, a shank assembly extending through and outwardly of said arcuate slot, through said elongated bar and secured at one end to said carrier, its other end

being screw-threaded, a nut assembly upon said last named screw-threaded end and normally bearing against said support, and means to reciprocate said dressing bar.

11. In a dresser for a stone mounted upon a pilot shaft, a support having an arcuate slot and a pivot-accommodating opening; pilot shaft-receiving-and-supporting means carried by said support, including a rotatable seat for said shaft; an elongated dressing bar; a stone-dressing device carried thereby; and dressing bar supporting, adjusting and locking means pivotally carried by said support to permit movement of said dressing bar carried by said supporting, adjusting and locking means so that the longitudinal axis of said dressing bar will intersect the axis of rotation of said seat, including an elongated bar, a carrier mounted thereon with said dressing bar slideable longitudinally therethrough, a pivot extending through and outwardly of said pivot-accommodating opening, and secured at one end to said carrier and provided with screw threads at its other end, a nut upon said other end and normally bearing against said support, a shank assembly extending through and outwardly of said arcuate slot, through said elongated

gated bar and secured at one end to said carrier, its other end being screw-threaded, including a shank and a sleeve disposed about the intermediate portions thereof, with said sleeve fixedly secured to said elongated bar against longitudinal movement in one direction therefrom, a nut assembly upon said last named screw-threaded end and normally bearing against said support, including an outer nut rotatably secured to said shank and an inner nut rotatably secured to said sleeve, with said outer nut bearing against said inner nut and said inner nut bearing against said support, and means to reciprocate said dressing bar.
